ROTARY STEAM ENGINE

Anatol David Iskols, Bronx, N. Y.

Application August 14, 1941, Serial No. 406,827

6 Claims. (Cl. 121—78)

My invention relates to improvements in rotary steam engines and the object is to provide a simple, rugged and easily maneuverable engine for use in ship propulsion.

In modern steamships the propeller is driven either by a reciprocating steam engine or by a steam turbine. Although these two types of steam engines have been developed to a high degree of perfection still both have inherently some unfavorable features which cannot be eliminated. Thus, the reciprocating engine requires the rather complicated crank mechanism in order to transform the straight motion of the piston into the rotating motion of the main shaft. This means, especially in triple or quadruple expansion engines, a great number of moving and working parts resulting in structure taking up much valuable space in length and height besides making it very heavy and costly to produce.

The steam turbine requires for its efficiency a very high speed of rotation while the propeller, just in the opposite, is more efficient at a relatively low speed of rotation; therefore, a reducing mechanism must be introduced between the turbine and propeller. Further, the steam turbine not being reversible requires an additional reverse turbine running idle when the ship is going ahead which is practically all the time; and many other such features.

In my improved rotary steam engine, as will be shown, the favorable features of both the above types of steam engines are retained while the unfavorable ones are practically eliminated, resulting in a very simple, compact, easy to manufacture engine with a great reduction in space, weight and cost.

How these results are attained is described in the following specification with reference to the annexed drawings in which:

Fig. 1 is a cross section of my rotary steam engine substantially on line AA of Fig. 2.

Fig. 2 is a longitudinal section and view partly in elevation.

Fig. 3 is a view on line BB of Fig. 2 showing the operating mechanism of the roller gate.

Fig. 4 is a front view specifically showing the operating mechanism of the steam admitting and cutting off valve.

Fig. 5 is a detail.

Fig. 6 is a cross section of my rotary with a double piston rotor.

Fig. 7 is an outline sketch of a compound rotary steam engine.

Figs. 8 and 9 are details of elements preventing steam leakage.

Fig. 10 shows diagrammatically the different phases of the working cycle.

5. My improved rotary steam engine belongs to the piston type rotaries and has as shown in Figs. 1 and 2 bolted to bedplate 1 the main cylinder 2 being preferably cast at both ends open and provided with flanges to which are bolted the end covers 3, 4. Main shaft 5 coaxial with cylinder 2 penetrates both end covers 3, 4 through suitable stuffing boxes and is supported by bearings 6, 7 mounted on bedplate 1 and adjustable horizontally and vertically to insure true coaxiality of main shaft 5 with cylinder 2.

Main shaft 5 carries fixedly mounted on it and extending the full length of the inner cylindrical space between end covers 3, 4 a runner 20 or rotor consisting of two parts: a relatively large cylindrical hub 8 coaxial with the main shaft and a piston 9 projecting radially from hub 8 to the inner surface of cylinder 2 and running in the concentric annular space between hub 8 and cylinder 2.

A blister 10 of cylindrical shape whose axis is parallel with the axis of cylinder 2 is cast integral with, extends the full length of cylinder 2 and is opening into the annular space. This blister being also open on both ends is closed by extensions of end covers 3, 4 and houses coaxially with it a roller gate 11 serving as an abutment which reaches hub 8 of the rotor and being rotatable can open and close the annular space as needed. Gate 11 is fixedly mounted on shaft 12 which is coaxial with blister 10, penetrating both end covers through suitable stuffing boxes and is supported by adjustable bearings 13 in brackets 14. One end of shaft 12 carries keyed to it arm 15 having a pin journaled in one end of spring 16 the other end of which is pivoted on post 17. Spring 16 being in tension tends to bring arm 15 into a vertical or neutral position and with it gate 11 into a horizontal which is its neutral position as shown in Fig. 10d.

On top of blister 10 is bolted to it steam chest 18 receiving steam from the boiler through pipe 19, nozzle 20 and containing poppet valve 21 which is lifted by forked arm 22 keyed on shaft 23, while spring 24 brings the valve down on its seat and closes it. The spindle of valve 21 may be connected to a dashpot 25 of conventional type to reduce the shock in seating the valve. Shaft 23 whose one end is journaled on

steam chest 18 is extended to the front, supported by bracket 26 and is carrying keyed to it the operating arm 21.

As shown in Figs. 1 and 10a when poppet valve 21 is open the admission steam flows through inlet port 28 in blister 10, passage 29 in gate 11 into the annular space in front of piston 9 causing the rotor to run in the direction of the arrow. At a certain predetermined point of the rotation of piston 9 valve 21 is seated, the steam admission is cut off, the steam enclosed between the then stationary gate 11 and the moving ahead piston 9 as shown in Fig. 10b is expanding until the piston arrives to the position shown in Fig. 10c and is beginning to open the annular space containing the expanded steam to the exhaust. At this point gate 11 also begins to rotate to its neutral position of Fig. 10d permitting the free passage of piston 9. As soon as the piston clears the gate the latter is made to snap back into its closed and stationary position Figs. 1 and 10a and the new working cycle is repeated.

This intermittent and periodic movement of gate 11 is produced by the following operating mechanism. For going ahead there is mounted fixedly on main shaft 5 disk 30 having a notch 31. Bell crank 32 pivoted in bracket 33 on bedplate 1 carries on one end a roller 34 which follows the contour of disk 30 while the other end is connected by toggle link 35 to arm 36 which can engage arm 15 keyed on shaft 12 which latter operates gate 11. Arm 15 which is fixedly keyed to shaft 12 has, as shown in Fig. 5, on one side of its hub a male jaw 37 forming, a partial clutch, by being in contact on one side only, with a similar male jaw 38 on hub of arm 36 which latter is loosely pivoted on shaft 12 and prevented from spreading by a standard collar.

When as shown on the right side in Fig. 3 toggle link 35 is set then arm 15, arm 36, toggle 35 and bell crank 32 form a closed link system whose movement is controlled on one side by disk 30 and on the other side by spring 16. So long as roller 34 follows the circular periphery of disk 30 this link system and gate 11 remain stationary in the position shown in Figs. 1, 3 and 10a, b, that is, gate 11 keeps the annular space between it and the piston closed. However, when notch 31 arrives opposite roller 34 spring 16 being in tension can pull arm 15 into its vertical position and turn with it gate 11 into its horizontal or neutral position of Fig. 10d giving piston 9 free passage. In further rotation notch 31 of disk 30 passes roller 34 the latter is pushed out by the disk periphery bringing the link system again in the position of Fig. 3 and the gate into its closed position of Fig. 1.

And so with each revolution of the engine this operation is repeated, the gate closing the annular space to let the admitted steam actuate the piston and at a certain point opening the annular space for a short time to let the piston pass and closing it again immediately for the next working cycle.

By tripping toggle 35 the unity of the above link system is interrupted, any movement of bell crank 32 cannot be transmitted to arm 15, spring 16 pulls it immediately into the vertical position and the gate into the neutral one where they remain stationary. The engine will stop, since no steam is admitted to the piston, and if there should remain some steam in the annular space

it is immediately exhausted or its pressure equalized on both sides of the piston.

When the rotation of the engine is reversed then disk 39 with a suitable notch, bell crank 40 pivoted in a bracket similar to 33 and carrying roller 41, toggle link 42 which is now set and arm 43 come into play, the gate 11 having been reversed, that is, brought into the position of Fig. 10e which is to the other hand of the one shown in Figs. 1 and 10a, b, c. This is brought about by setting astern toggle 42, the ahead toggle 35 having previously been tripped, resulting in male jaw 45 on hub of arm 43, Fig. 5, now coming in clutch contact with male jaw 44 on hub of arm 15 so that 40, 42, 43 form now the closed link system operating arm 15. The operation of this astern link system is similar to the ahead link system described above and the picture is similar to Fig. 3 only to the other hand, that is, toggle 35 is tripped, toggle 42 is set, arm 15 points to the left and spring 16 is on the left.

Working steam is admitted to the engine and at the proper time cut off by poppet valve 21 being lifted and opened by forked arm 22 and closed by spring 24. This operation is produced for both going ahead or astern by the following mechanism. On main shaft 5 are fixedly mounted disk 45 with cam 46 for going ahead and disk 47 with cam 48 for going astern. Lever 49 pivoted on bedplate 1 operates link 50 carrying ahead roller 51 which is in the plane of ahead cam 46 and astern roller 52 which is in the plane of astern cam 48. The other end of link 50 is connected by rod 54 with arm 21 on shaft 23 which latter by means of forked arm 22 lifts valve 21. Bracket 53 has several notches to hold lever 49 in its different positions.

When running ahead, as shown in Fig. 4, lever 49 is held in its middle position bringing ahead roller 51 on top of disk 45 to be operated by ahead cam 46 which lifts together with the roller 51 the whole link system 50, 54, 21 and simultaneously valve 21 admitting steam to the engine. As soon as ahead cam passes roller 51 spring 24 pushes down valve 21 together with this link system thus cutting off the steam.

In running astern lever 49 is brought into its outward position bringing astern roller 52 on top of disk 47 to be operated by cam 48 while ahead roller 51 is brought beyond reach of ahead cam 46. The operation of the link system is then the same as for going ahead.

By putting lever 49 into its inward position both ahead and astern rollers are brought beyond reach of either cam, spring 24 will keep valve 21 closed and the engine will stop.

It will be noted that by varying the position of lever 49 slightly to right or left of its middle position the steam cut off can be varied also.

In all steam engines the question of steam leakage is of great importance for the economic efficiency of the engine. In most suggested rotary steam engines this question is not considered at all; in others the prevention of steam leakage is attempted by reducing the clearances between the rotating and adjacent parts to a very close fit which is only a temporary expedient and quickly destroyed through wear in the bearings, inaccuracies in assembling and other causes.

In my improved rotary steam engine steam tightness is obtained in an entirely novel way, as a matter of fact, is produced by the working steam itself. It, therefore, permits of relatively larger clearances between the internal rotating

and adjacent parts, resulting in lower manufacturing costs and easier assembling. The means to obtain these results are illustrated in Fig. 8 showing the clearance gap between gate 11 and hub 8 of the rotor and in Fig. 9 showing the clearance gap between piston 9 and main cylinder 2.

As shown in Fig. 8 a laminated bundle 55 consisting of a number of thin metal strips of varying width and extending the whole length of gate 11 is placed in a suitable groove of the gate obliquely to but not protruding, when straight, beyond its periphery and held in place by retaining bar 56 and necessary number of screws. Over the widest strip the gate is slightly undercut forming a pocket for admitting the working steam. Now, when rotor is running in direction of arrow there is a higher pressure in the space at the right of bundle 55 containing the working steam than in the space at left which is exposed to the exhaust steam. Or, the steam pressure on top of bundle 55 is greater than on the bottom resulting in the deflection of the laminae until their free ends make contact with the hub 8 of the rotor sealing the clearance gap and preventing any steam leaking to the exhaust side. When the steam pressure is equalized on both sides the laminae will become straight again and the contact broken.

On piston 9 which is rotatable in both directions two such oblique laminated bundles as 55 would be required which, however, as shown in Fig. 9, can be combined in one bundle 57 of laminae shaped in form of a flat V held by a single retaining bar 58 and necessary number of screws, each branch working independently of the other. The piston is also undercut on both sides under the widest lamina forming pockets for the working steam.

Thus, when piston 9 rotates in direction of arrow the left side branch of bundle 57 which is exposed to the working steam will under the steam pressure deflect and make with its free end contact with main cylinder 2 and seal the clearance gap, while the right side branch being exposed equally on top and bottom to the exhaust steam will remain straight. Similar and suitably formed laminated bundles can be applied on other clearance gaps to prevent leakage there.

In Fig. 6 is shown a cross section of my improved rotary steam engine having a rotor with two diametrically opposite pistons. The main cylinder has two also diametrically opposite blisters housing each a gate for each piston similar to Fig. 1 and the chest has two pipe connections leading steam to each piston. Both gates are interconnected by linkage shown diagrammatically in heavy lines, thus working as a unit and requiring one operating mechanism of the type shown in Fig. 3 for one of the two gates with the exception that disks 30, 39 require each two diametrically opposite notches 31. Similarly the steam admitting poppet valve 21 requires only one operating mechanism as shown in Fig. 4 with the exception that disks 45, 47 require each two diametrically opposite cams 46, 48.

This double piston type of my improved rotary has the advantage of more uniform torque, better balancing of the rotor and most importantly the elimination of piston pressure on the main bearings.

The operation of my improved rotary steam engine on board ship is as follows. When at rest both toggle links 35, 42 are tripped, gate 11 is in its neutral position, lever 49 in its extreme inward

position keeping both rollers 51, 52 beyond the operation of cams 46, 48; therefore, steam valve 21 is closed and no steam is admitted to the engine.

To start running ahead the ahead toggle link 35 is set, lever 49 is brought into its middle position bringing ahead roller 51 in contact with ahead cam 46, valve 21 is lifted admitting steam to the engine and it starts running ahead. Should at the start the ahead cam 46 be in a position away from ahead roller 51 and so valve 21 remain closed, then steam from a small hand operated auxiliary valve is admitted to the engine to start it, as is the usual marine practice.

To reverse the engine, that is, to change from going ahead to going astern the ahead toggle 35 is tripped causing gate 11 to assume its neutral position, as shown in Fig. 10d, and preventing steam from reaching the piston so that the engine will stop. Then astern toggle 42 is set and lever 49 brought into its outward position bringing astern roller 52 into operation by astern cam 48 and the engine will run astern.

The toggle links 35 and 42 will be interlocked so that they cannot be set at the same time; only one can be set at a time while the other remains tripped, however, both can be tripped simultaneously.

All the above described manipulations can through suitable linkage be operated from a central station in the engine room or even may be led to the bridge to be controlled from there.

Figs. 1 to 6 illustrate my improved rotary steam engine wherein the steam is expanded in a single stage. Since my rotary works on the uniflow principle this one stage steam expansion would not affect its efficiency to the same extent as in a reciprocating engine. However, especially for larger units, I prefer to make the steam work in two or more stages. Fig. 7 shows in outline a compound rotary steam engine in which a HP rotary works on the high pressure stage of the steam cycle, exhausting into the valve chest of the larger low pressure rotary working on the low pressure stage of the steam cycle and exhausting into the condenser. Otherwise the construction of both rotaries is the same as described above. Both can be mounted on one shaft as in a single screw ship or on separate shafts as in twin screw ships.

Although my improved rotary steam engine is intended primarily for use on steamships it also can be used with advantage on land where reversible engines are required, for example, in steel rolling mills, mining hoists and other plants. In cases where the reversibility is not required the unnecessary parts can be omitted, further simplifying my rotary.

In the above specification and annexed drawings my improved rotary steam engine is shown in its simplest embodiment; however, other modifications and variations are possible within the spirit and scope of my invention.

I am aware that piston type rotary steam engines have been previously suggested, although never made workable, therefore, I do not claim this type broadly as my invention. However the peculiar combination of the main working with other assisting elements, though all individually well known, but through novel functioning, creating a practical and efficient rotary steam engine is what I can claim as my invention.

I claim:

1. A rotary steam engine of the piston type, comprising a main cylindrical body closed at both

ends, a main shaft coaxially located in the main cylindrical body, a rotor hub on said shaft and within said cylindrical body forming with said cylindrical body, a concentric annular space, a piston projecting radially from said hub to the inner cylindrical surface of said cylindrical body, a part-cylindrical valve chamber on said cylindrical body extending longitudinally thereof and communicating with said main cylindrical body, the axis of said valve chamber being parallel to the axis of said cylindrical body, the valve chamber being closed at its opposite ends, a shaft within said valve chamber co-axial therewith, a roller valve within said valve chamber and on said last mentioned shaft, means to intermittently and periodically oscillate said roller valve through predetermined angles in timed relation to the rotation of said piston in one direction, means to render said last means inoperative, said piston being formed with a groove in a surface thereof adjacent an inner surface of said cylindrical body, and a bundle of laminated flexible strips fixed to the piston and projecting into said groove, the outer ends of said strips being in a common plane and normally spaced from the inner surface of said main cylindrical body, said bundle of strips being spaced from the bottom of the groove, whereby steam within the groove is adapted to force the outer ends of said strips against the inner surface of said cylindrical body, to seal the space between the piston and said inner surface.

2. A rotary steam engine of the piston type, comprising a main cylindrical body closed at both ends, a main shaft co-axially located in the main cylindrical body, a rotor hub on said shaft and within said cylindrical body forming with said cylindrical body, a concentric annular space, a piston projecting radially from said hub to the inner cylindrical surface of said cylindrical body, a part-cylindrical valve chamber on said cylindrical body extending longitudinally thereof and communicating with said main cylindrical body, the axis of said valve chamber being parallel to the axis of said cylindrical body, the valve chamber being closed at its opposite ends, a shaft within said valve chamber co-axial therewith, a roller valve within said valve chamber and on said last mentioned shaft, means to intermittently and periodically oscillate said roller valve through predetermined angles in timed relation to the rotation of said piston in one direction, means to render said last means inoperative, said piston being formed with a groove in a surface thereof adjacent an inner surface of said cylindrical body, and a bundle of laminated flexible strips fixed to the piston and projecting into said groove, the outer ends of said strips being in a common plane and normally spaced from the inner surface of said main cylindrical body, said bundle of strips being spaced from the bottom of the groove, whereby steam within the groove is adapted to force the outer ends of said strips against the inner surface of said cylindrical body, to seal the space between the piston and said inner surface, said strips being of gradually increasing width.

3. A rotary steam engine of the piston type, comprising a main cylindrical body, a main shaft coaxially located in the main cylindrical body, a rotor hub on said shaft and within said cylindrical body forming with said cylindrical body a concentric annular space, two diametrically opposite pistons projecting radially from said hub to the inner cylindrical surface of said cylindrical body,

5 cal body, two diametrically opposite part-cylindrical valve chambers on said cylindrical body extending longitudinally thereof and communicating with said main cylindrical body, the axes 10 of said valve chambers being parallel to the axis of said cylindrical body, the valve chambers being closed at their opposite ends, a shaft within each of said valve chambers co-axial therewith, both these shafts being interconnected for simultaneous operation, a roller valve within each 15 of said valve chambers, means to intermittently and periodically oscillate said roller valves through predetermined angles in timed relation to the rotation of said pistons in one direction, means to render said last means inoperative, said pistons being each formed with a groove in a surface thereof adjacent an inner surface of said cylindrical body, and a bundle of laminated flexible strips fixed to each piston and projecting 20 into said groove, the outer ends of said strips being in a common and normally spaced from the inner surface of said main cylindrical body, said bundle of strips being spaced from the bottom of the groove, whereby steam within the groove 25 is adapted to force the outer ends of said strips against the inner surface of said cylindrical body to seal the space between the pistons and said inner surface.

4. A rotary steam engine of the piston type, 30 comprising a main cylindrical body, a main shaft coaxially located in the main cylindrical body, a rotor hub on said shaft and within said cylindrical body forming with said cylindrical body a concentric annular space, two diametrically opposite pistons projecting radially from said hub to the inner cylindrical surface of said cylindrical body, two diametrically opposite part-cylindrical valve chambers on said cylindrical body extending longitudinally thereof and communicating with said main cylindrical body, the axes 35 of said valve chambers being parallel to the axis of said cylindrical body, the valve chambers being closed at their opposite ends, a shaft within each of said valve chambers co-axial therewith, both these shafts being interconnected for simultaneous operation, a roller valve within each of said valve chambers, means to intermittently and periodically oscillate said roller valves through predetermined angles in timed relation to the rotation of said pistons in one direction, means to render said last means inoperative, said pistons being each formed with a groove in a surface 40 thereof adjacent an inner surface of said cylindrical body, and a bundle of laminated flexible strips fixed to each piston and projecting into said groove, the outer ends of said strips being in a common and normally spaced from the inner surface of said main cylindrical body, said bundle of strips being spaced from the bottom of the groove, whereby steam within the groove 45 is adapted to force the outer ends of said strips against the inner surface of said cylindrical body to seal the space between the pistons and said inner surface, said strips being of gradually increasing width and disposed at an acute angle to the adjacent surface of inside of said cylindrical body.

5. A steam engine of the rotary piston type, 50 comprising a cylinder, a piston rotatably mounted therein, a valve chamber on said cylinder communicating therewith and co-axial therewith, a valve mounted for oscillation within said valve chamber, a cam mounted for rotation with the piston and disposed externally of the cylinder, 55 follower means adapted to contact said cam,

spring means to rotate said valve, and toggle means interconnecting said valve with said follower means, said toggle means being adapted in one position thereof to connect the valve and follower means for concurrent movement, and in another position thereof to permit movement of the valve without movement of the follower means.

6. A steam engine of the rotary piston type, comprising a cylinder, a piston rotatably mounted therein, means to provide a seal between the rotating piston and the inner surface of the cylinder, a valve chamber on said cylinder communicating therewith, a valve mounted for move-

ment within the valve chamber, cam means connected for rotation with the piston and disposed externally of the cylinder, spring means to move said valve, a member engaging the cam and adapted to be moved thereby and mechanism interconnecting the valve with the cam engaging member, said mechanism being adapted in one position thereof to connect the valve and cam engaging member for concurrent movement and in another position thereof to permit movement of the valve without movement of the cam engaging means.

A. DAVID ISKOLS.
